UNITED STATES PATENT OFFICE.

WILLIAM J. SELLECK, OF RIVERSIDE, CONNECTICUT.

CONVEYER-BELT.

SPECIFICATION forming part of Letters Patent No. 705,876, dated July 29, 1902.

Application filed May 31, 1902. Serial No. 109,601. (No model.)

To all whom it may concern:

Be it known that I, WILLIAM J. SELLECK, a citizen of the United States, residing at Riverside, county of Fairfield, State of Connecticut, have invented a certain new and useful Improvement in Conveyer-Belts; and I declare the following to be a full, clear, and exact description of the invention, such as will enable others skilled in the art to which it pertains to make and use the same, reference being had to the accompanying drawings, which form a part of this specification.

My invention relates generally to conveyers, and more particularly to endless flexible conveyer-belts which are given a trough-shaped cross-section while carrying the material.

In order to prevent the material carried by the conveyer from falling off the side edges thereof, it is desirable to provide inclined guides beneath the conveyer-belt to maintain the sides at a higher level than the center thereof. The transverse bending of the belt necessary to incline its sides results in the belt soon wearing out and breaking along the lines between the central and side portions. It has been proposed heretofore to construct conveyer-belts with a central horizontal section and side sections adapted to be inclined with respect to the central section to form a trough. The side sections have either overlapped the edges of the central section and been secured thereto by rivets passing through the overlapped portions or strips have been interposed between and secured to the adjacent edges of the central and side sections. It is evident, however, that the objection above noted is not avoided in either of the constructions mentioned, inasmuch as in the former the portions of the side sections adjoining the central section must assume the wear incident to the formation of the trough-shaped cross-section and in the latter the interposed strips serve as hinges and soon wear out through the necessarily constant flexure thereof.

The object of my invention is to provide a durable endless conveyer-belt which will readily assume a trough-shaped cross-section without bending the material of which the belt is composed, and consequently avoiding

the wear to which similar belts heretofore constructed have been subjected.

A further object of my invention is to provide a conveyer-belt which will be simple in construction, inexpensive in manufacture, and durable and efficient in use.

My invention, generally stated, consists in a conveyer-belt composed of a central and side sections flexibly united at their adjoining edges by interlocked lacings.

My invention will be more fully described hereinafter with reference to the accompanying drawings, in which the same is illustrated as embodied in a convenient and practical form, and in which—

Figure 1 is a cross-section showing my conveyer-belt supported by guide-rollers; Fig. 2, a fragmentary plan view of my improvement, and Fig. 3 an enlarged sectional fragmentary view showing the means for uniting the adjoining edges of the central and a side section.

Similar reference characters are used to indicate similar parts in the several figures of the drawings.

Reference-letter A designates the central section of the conveyer-belt, to the side edges of which are flexibly secured side sections A' and A².

Suitable guides are provided for supporting the central section A in a horizontal position and maintaining the side sections A' and A² in inclined positions, so as to impart to the conveyer-belt a trough-shaped cross-section, thereby preventing the material which is carried on the belt from falling off of the sides thereof. In Fig. 1 of the drawings I have indicated a central cylindrical roller B for supporting the central section A of the conveyer-belt, while side rollers B' and B² support the side sections A' and A² of the conveyer-belt in the inclined positions indicated. The roller B is suitably journaled in the conveyer-frame—as, for instance, by means of concentric pins b, while similar pins b' and b² rotatably support the inclined rollers B' and B².

In order that the side sections may freely move relatively to the central section without bending either the central or side sections, I have provided lacings which pass through

openings in the adjoining edges of the sections and which serve as hinges to permit the relative movement between the side and central sections of the conveyer-belt. A lacing 5 a , preferably in the form of a spiral, passes through each edge of the central section at comparatively short intervals, as indicated in Fig. 2. A similar spiral lacing a' passes through the inner edge of the side section A' 10 at intervals corresponding to the spaces between the convolutions of the spiral lacing a' . The portions of the spirals a and a' which project beyond the edges of the respective sections are overlapped, so as to form a series 15 of registering loops, through which is passed a flexible wire or, preferably, a leather thong C' . A spiral lacing a^2 passes through a series of perforations in the inner edge of the side section A^2 to engage a spiral lacing a , secured 20 to the adjoining edge of the central section A . The projecting portions of the convolutions of the spirals a and a^2 overlap, so as to form a passage, through which is inserted a leather thong C^2 . 25 Before the leather thongs C' and C^2 are inserted through the overlapped lacings the latter are preferably flattened, as indicated in Fig. 3, to form a passage-way of the requisite size to receive the thongs C' and C^2 . 30 The lacings are securely held in the edges of the sections of the belt and are not required to move in the openings therein when the side sections assume the inclined positions to form a trough-shaped cross-section. The 35 movement of the side sections with relation to the central section is permitted by the movement of the overlapped lacings with respect to each other. While the side sections may freely move into the requisite inclined 40 positions, they are rigidly secured to the central section owing to the thongs C' and C^2 , which couple together the overlapped lacings. The material of which the sections of the 45 conveyer is formed may be leather, rubber, cloth, wire, woven fabric, or any other suitable flexible material. The lacings a , a' , and a^2 are preferably formed of wire.

From the foregoing description it will be observed that I have invented a conveyer-belt 50 capable of assuming a trough-shaped cross-section to support the carried material

without subjecting the material of which the conveyer-belt is formed to any bending whatever, the relative movement between the central and side sections being permitted by the loose interlocked engagement between the lacings. 55

Having now fully described my invention, what I claim as new, and desire to secure by Letters Patent, is— 60

1. The combination with a conveyer-belt consisting in a plurality of longitudinal sections, of a hinge flexibly uniting said sections composed of parts movably joined together and rigidly secured to the adjoining edges of 65 said sections.

2. The combination with a conveyer-belt composed of a plurality of longitudinal sections, of lacings passing through the adjoining edges of said sections, and means for 70 flexibly uniting said lacings.

3. The combination with a conveyer-belt composed of a plurality of longitudinal sections, of coil-spring lacings passing through each of the adjoining edges of said sections, 75 and a thong extending through the overlapped convolutions of the lacings.

4. The combination with a conveyer-belt composed of a plurality of longitudinal sections, of coil-spring lacings having elliptical 80 convolutions passing through the adjoining edges of said sections, the projecting portions of said convolutions being overlapped, and a leather thong extending through the registering overlapped convolutions of said lacings. 85

5. In a conveyer-belt, the combination with central and side sections, of a hinge flexibly uniting said sections composed of parts movably joined together and rigidly secured to 90 the adjoining edges of said sections.

6. In a conveyer-belt, the combination with central and side sections, of lacings passing through the adjoining edges of said sections, and means for flexibly uniting said lacings. 95

In testimony whereof I sign this specification in the presence of two witnesses.

WILLIAM J. SELLECK.
